UNITED STATES PATENT OFFICE.

HENRY A. MEYER, OF CINCINNATI, OHIO, ASSIGNOR TO WOLF ELECTRICAL PROMOTING COMPANY, OF CINCINNATI, OHIO, A CORPORATION OF OHIO.

ADJUSTABLE PRESSER-FOOT FOR CLOTH-CUTTING MACHINES.

No. 926,815.

Specification of Letters Patent.

Patented July 6, 1909.

Application filed March 20, 1909. Serial No. 484,819.

To all whom it may concern:

Be it known that I, HENRY A. MEYER, a citizen of the United States, residing at Cincinnati, in the county of Hamilton and State of Ohio, have invented certain new and useful Improvements in Adjustable Presser-Foots for Cloth-Cutting Machines; and I do hereby declare the following to be a full, clear, and exact description of the invention, such as will enable others skilled in the art to which it appertains to make and use the same.

This invention relates to a class of machines used for cutting textile fabrics and other materials, and more particularly machines of the class referred to in which a reciprocating knife is employed to cut a number or series of superposed layers of fabric in accordance with a pattern or markings upon the uppermost layer of fabric, the cutting being effected by the reciprocating knife as the machine is moved bodily and guided over the surface of a table or other support upon which the fabric is placed.

The object of my present invention is to provide an improved and more efficient presser-foot, such as used in the class of machines referred to, arranged directly in front of the knife, so as to bear down upon the layers of fabric as the machine is moved and guided along the lines upon which the cloth is to be cut, and adapted to avoid the liability of accidental adjustment, by failure of the securing means ordinarily employed to perform the desired function.

Various contrivances have heretofore been employed for clamping the presser-foot to the standards of fabric cutting machines, a common method or means being a screw or screws for securing the presser-foot at different elevations, but in practice it has been found that, on account of the vibrations and strain due to the reciprocatory movement of the knife, and the opposing pressures, or in other words, the pressure due to the cutting of the fabric on the downward movement of the knife and the opposing pressure due to the fabric being lifted by the knife on the upward movement of the latter, the set screws work loose and allow the presser-foot to be adjusted accidentally, causing inconvenience and trouble. Another method or means of fastening the presser-foot with provision for adjustment is to use a rack and pinion, the presser-foot being secured to the

lower end of a vertically adjustable rack or toothed bar which is engaged by the pinion for effecting the desired adjustment, but this method is objectionable in practice, because the teeth of the rack and pinion soon become clogged with dust, lint, etc., and the arrangement is too bulky, necessarily interfering with the sight of the markings on the fabric.

My invention overcomes the objectionable features of the several devices above mentioned, and instead of the presser-foot being liable to come loose, by reason of the vibrations of the machine, it will become even more securely fixed, owing to a constant spring pressure exerted on a trigger-like locking device having a serrated or corrugated surface engaging the rod or bar which carries the presser-foot. My improved device is also adapted to be readily adjusted without requiring the operator to release his hold upon the machine, by merely exerting the pressure of a finger on the trigger which controls the position of the presser-foot bar; such operation being performed if desired while the machine is in operation.

In the accompanying drawings, which are to be taken as a part of this specification, I have illustrated my present improvement applied to a cloth-cutting machine having a vertically movable knife to which a reciprocatory movement is imparted by an electric motor mounted on the machine. The improvement, however, is applicable to other types of machines, whether electrically actuated or otherwise, but is specially useful in connection with the type of machine shown.

In said drawings, Figure 1 represents a perspective view in dotted lines of a cloth cutting machine with a reciprocating knife, having my improved presser-foot applied thereto, the latter being shown in full lines; Fig. 2 is a side view, on an enlarged scale, of a portion of the machine standard with my improved adjustable presser-foot applied thereto, illustrating the hand of the operator about to effect an adjustment of the presser-foot while the machine is in operation; Fig. 3 is a transverse horizontal sectional view taken through the presser-foot supporting bracket or plate and Fig. 4 is a vertical sectional view taken on the line 4—4 of Fig. 4.

Referring to said drawings, in which the same reference letters are used to denote corresponding parts in different views, the letter A may denote an electrically operated or

other type of fabric cutting machine having my improved presser-foot thereon, said machine having a standard B, and a knife C, operatively connected with the motor for imparting a reciprocatory movement to the knife. The standard B is supported in an upright position upon a foot-plate D and is provided with a handle E by which the machine is moved bodily over the table, the foot-plate or base D being arranged underneath the lowermost layer of fabric so as to lift the entire body of fabric up into position to be cut by the knife. Near and preferably below the handle E is a bracket or support F, which may be bolted or otherwise secured to said standard, and has at one end a vertically disposed socket f in which is fitted a vertically movable bar G carrying a foot-plate g at its lower end. The bar G is preferably 20 rectangular in cross-section and may be channeled at one side, as shown, and has smooth surfaces adapting it to slide freely up and down within the correspondingly smooth bore of the socket f. When the machine is in use the presser-foot bears down upon the layers of fabric and in order that it may be adjusted and fixed at any desired elevation; as required from time to time in cutting different thicknesses of fabric, or a greater or less 25 number of layers, a locking device is secured upon the bracket F, and adapted to operate in such manner that the operator may easily and quickly release and adjust the presser-foot while the machine is either moving or stationary. This locking device may consist of a trigger-like lever or dog H, arranged beside and parallel with the bracket F, and having a lug h fitted in a slot extending longitudinally of said bracket, the lug h being 30 pivoted on a bolt or rivet passing through apertures in the bifurcated arms of the bracket formed by the slot therein. The dog H has at one end a projection or tooth h¹ adapted to engage the vertically movable 35 presser-foot bar G and hold the same in a fixed position. Said dog is preferably made of hardened steel and the tooth h¹ being highly tempered and having preferably a serrated or corrugated surface h² for engagement with the presser-foot bar, will in a 40 measure take into or slightly indent said bar sufficiently to adapt the presser-foot to withstand the severe strains to which it is subjected and avoid liability to accidental adjustment. The longer arm h³ of the dog or 45 lever H is pressed outwardly by a suitable spring that may be interposed between said arm and the bracket or support F; a coiled spring I being shown, having its opposite ends seated in recesses i formed in the confronting surfaces of the bracket and longer arm h³ of the lever, as shown in Fig. 3 of the drawings. By this arrangement the spring 50 has a constant tendency to force the tooth h² more tightly against the presser-foot bar

and the grip of the tooth is tightened by the vibrations of the machine.

I thus provide a very simple, strong, durable and efficient adjustable presser-foot with a locking device, consisting of few parts that may be easily assembled and attached to any ordinary machine standard, carrying a reciprocating knife; said device enabling the operator to easily and quickly raise or lower the presser-foot, with provision for great 70 nicety of adjustment, without requiring any set screw or bolt to be loosened, and again tightened, with consequent trouble and loss of time due to the stoppage of the machine for such purpose, and without liability to 75 accidental adjustment or displacement of the presser-foot when the machine is in operation, which results from the unavoidable loosening of set screws, bolts and nuts, due to the vibrations of the machine and the opposing pressure of a rapidly reciprocating knife. The described construction also obviates the objections incident to using adjusting mechanism, such as heretofore employed, having toothed surfaces or projections upon which lint and dust may collect 80 so as to seriously interfere with the sight of the operator in following the pattern or markings upon the cloth that is being cut. It also enables the operator, without releasing his hold upon the machine, to readily adjust the presser-foot, by pressing his forefinger against the long arm of the pivoted lever or dog, so as to release and allow the presser-foot to descend by gravity, or to be 85 raised by pressure of the presser-foot upon the underlying layers of cloth, and the instant the dog is released, the presser-foot will be again locked in the desired position.

Having thus described my invention, what I claim as new and desire to secure by Letters Patent of the United States is:—

1. In a fabric cutting machine, an adjustable presser-foot and means for securing the same at different elevations, comprising a suitable holder and guide on the machine standard a rod or bar carrying a presser-foot and vertically movable in said guide, a dog hinged beside said holder having a toothed end engaging said bar, and means for forcing said tooth into engagement with said bar adapted to yield to opposing pressure and release the bar.

2. In a fabric cutting machine, an adjustable presser-foot and means for securing the same at different elevations, comprising a bracket adapted to be secured to the machine standard and having a vertically disposed socket or guide projecting in front of the standard, a presser-foot bar fitted in said socket, a dog pivoted at one side of said bracket and having a tooth at one end, and a spring operating to force said tooth into contact with said presser-foot bar.

3. An adjustable presser-foot bar and

means for holding the same in alinement with the reciprocating knife of a fabric cutting machine, a pivoted dog beside said holding means having a tooth engaging said bar, and means for forcing said tooth into engagement with said bar; said tooth having a serrated surface for contact with the bar.

4. In combination with the machine standard, a bracket thereon having a slot 10 therein and a socket at the end of the slot, a rod or bar in said socket carrying a presser-foot, a dog pivoted at one side of said bracket having a tooth engaging said bar, and a spring interposed between the dog and 15 bracket for forcing said tooth into contact with said bar.

5. An adjustable presser-foot for fabric cutting machines comprising a vertically movable bar carrying a presser-foot, a supporting plate having a lever pivoted thereto and a socket on said support in which said bar is fitted, said lever having at the end of one arm a tooth engaging said bar, and a spring for holding said tooth in engagement with said vertically movable bar. 20

In testimony whereof I affix my signature, in presence of two witnesses.
